UNITED STATES PATENT OFFICE.

VICTOR H. JENNINGS, OF WORCESTER, MASSACHUSETTS, ASSIGNOR TO CROMPTON & KNOWLES LOOM WORKS, OF WORCESTER, MASSACHUSETTS, A CORPORATION OF MASSACHUSETTS.

DEVICE TO PREVENT ROTATION OF BOBBINS.

Application filed October 28, 1925. Serial No. 65,418.

- This invention relates to multi-color weft replenishing mechanisms of the type set forth in Patent No. 1,030,748 and it is the general object of the invention to provide 5 the walls of the several bobbin compartments with yielding surfaces having a relatively high coefficient of friction to the end that the butts of the bobbins may be resisted in their normal tendency to rotate.
- 10 It is found when bobbins are required to wait for any length of time before transfer in the usual form of multi-color weft replenishing mechanisms that due to the vibration of the loom they tend to rotate on their axes, this rotation in some instances resulting in breaking of the thread which extends to the thread holder. Various devices have been suggested to correct this defect but most of them have involved a 15 moving part. It is a further object of my invention to overcome this tendency on the part of the bobbins to rotate by lining the walls of the bobbin compartments with a substance such as rubber.
- 20 25 It is found that slight irregularities exist in the width of the various bobbin compartments due to the movement of the pattern in the sand during the molding process and it is found that some of the compartments are wide enough to permit vibration of the bobbins to an undesirable degree. It is a still further object of the invention to 30 compensate for variations in the width of the compartments by providing an elastic element conveniently applied to the compartment walls and stretched to vary its thickness so that a relatively thick part of the element will be in a wide compartment to render the same of desirable width.
- 35 40 With these and other objects in view which will appear as the description proceeds, my invention resides in the combination and arrangement of parts hereinafter described and set forth in the claims.
- 45 In the accompanying drawings wherein I have shown three different forms of my invention,

Fig. 1 is a vertical transverse section through a portion of a multi-color weft replenishing mechanism looking toward the butt end of the bobbins, and having the elastic element applied thereto.

Fig. 2 is a horizontal section on line 2—2 of Fig. 1,

Fig. 3 is an enlarged vertical section on line 3—3 of Fig. 2, and

Fig. 4 is a view similar to Fig. 2 but showing modified forms of the invention.

Referring to the drawings it will be seen that I have provided a weft replenishing mechanism frame 10 provided with flanges 11, 12, 13, 14, and 15 which define bobbin compartments A, B, C, and D which as shown in Fig. 2 are sufficiently wide to permit free motion of the heads of the bobbins located therein. Cradles or other controlling devices 16 are located one at the bottom of each of the compartments and are movable by mechanism not shown to release the bobbins one at a time so that they may move to transfer position.

In carrying out my invention I employ elastic bands 20 which may be stretched around the flanges 12 and 14. While I have shown rubber bands associated with but two of the flanges it is to be understood that all the flanges may be provided with the rubber bands if found desirable.

For purposes of illustration it is assumed that the compartments C and D are of unequal width, compartment D being somewhat wider than the compartment C and in order to correct this defect the rubber band may be stretched so that the thin part thereof is in compartment C and the thick part in compartment D. In this way slight inaccuracies in the width of the compartments are corrected. The band is shown as of equal thickness on both sides of the flange 12, it being assumed that compartments A and B are of equal width and in both instances the surface of the band tends to hold the heads of the bobbins against rotation. Said bobbins, however, are free to move downwardly without interruption as the cradles 16 operate.

By referring to Fig. 4 it will be seen that flange 12 is surrounded by a tubular band 21 the inner portion of which hugs tightly against the flange while the outer portion is loose and can conform itself somewhat to the contour of the bobbin.

The flange 14 in said Fig. 4 is shown as provided with a pair of narrow rubber bands 22 so proportioned as to fit between the rings 17 on the bobbin head. In these modified forms the feature set forth in Fig. 3 is present, the frictional contact between the

flange and the inner surface of the band overcoming any tendency on the part of the band to assume a uniform cross section after it has been set to a position corresponding to that shown in Fig. 3.

From the foregoing it will be seen that I have provided a very simple means for compensating for the slight irregularities which occur in the width of the bobbin compartments and that the means employed present to the bobbins a surface having a relatively high coefficient of friction. In this way the compartments which are of objectionable width may be made narrower by 15 a substance having a surface offering resistance to the rotation of the bobbins.

Having thus described my invention it will be apparent that changes and modifications may be made therein by those skilled 20 in the art without departing from the spirit and scope of the invention, and I do not wish to be limited to the details herein disclosed but what I claim is:

1. In a weft replenishing loom, a frame, 25 flanges extending therefrom and defining bobbin compartments, and resilient means carried by one of the flanges and common to two adjacent compartments, said means presenting a surface having a relatively high 30 coefficient of friction to the bobbins and capable of movement as a whole in a direction parallel to the compartment to assume a plurality of relative positions with respect to the flange to vary the width of the compartments.

2. In a weft replenishing mechanism, 35 means defining a pair of adjacent bobbin compartments, a wall between and common to said compartments, and resilient means supported by and extending on both sides 40 of the wall to be common to both compartments, said means being movable as a whole with respect to the wall in a direction parallel to the compartments so that the greater 45 portion thereof may lie in one compartment and the lesser portion thereof in the other compartment to compensate for slight variations in the width of the compartments.

3. In a weft replenishing mechanism, 50 means defining a pair of adjacent bobbin compartments, a wall between and common to said compartments, and a continuous resilient member stretched around and supported on the wall and movable relatively 55 to the wall to have the larger portion thereof in one compartment and the smaller portion thereof in the other compartment to

compensate for variations in the width of the compartments.

4. In a weft replenishing mechanism, 60 means defining a pair of adjacent bobbin compartments, a wall between and common to said compartments, and a continuous resilient member stretched around and supported on the wall and movable relatively to 65 the wall to have the larger portion thereof in one compartment and the smaller portion thereof in the other compartment to compensate for variations in the width of the compartments, said member having a surface 70 with a relatively high coefficient of friction to hold the same on the wall and also to resist rotation of the bobbins in the compartment.

5. In a weft replenishing mechanism, 75 means defining a pair of adjacent bobbin compartments, a wall between and common to the compartments, and a resilient member held to the wall and capable of being stretched to have the thicker portion thereof 80 in one compartment and the thinner portion thereof in the other compartment to compensate for variations in the width of the compartments.

6. In a weft replenishing mechanism, 85 means defining a pair of adjacent bobbin compartments, a wall between and common to both compartments, and a continuous rubber band mounted on the wall and common to both compartments, said rubber band 90 being movable relatively to the wall and held frictionally thereto to have the thicker portion thereof in one compartment and the thinner portion thereof in the other compartment to compensate for variations in 95 the width of the compartments.

7. In a weft replenishing loom, a frame, 100 a pair of spaced parallel flanges, a third flange parallel to and lying between the pair of flanges to form with the latter a pair of bobbin compartments, and an element 105 stationary and held to the third flange and lying partly in each of the compartments, the portion of the element in one compartment being thinner than the portion thereof lying in the other compartment, said element being movable as a whole relatively to the third flange to assume different positions relatively thereto to vary the width of the compartments.

In testimony whereof I have hereunto affixed my signature.

VICTOR H. JENNINGS.
